US00D656808S

(12) **United States Design Patent**
Arvinte et al.

(10) **Patent No.:** **US D656,808 S**
(b4) **Date of Patent:** ** Apr. 3, 2012

(54) **CORNER SANDING SPONGE**

(75) Inventors: **Roméo Arvinte**, Laval-des-Rapides (CA); **François Panfili**, Berthierville (CA)

(73) Assignee: **A. Richard Tools Co./Outils A. Richard Co.**, Berthierville, Quebec (CA)

(**) Term: **14 Years**

(21) Appl. No.: **29/384,463**

(22) Filed: **Jan. 31, 2011**

(30) **Foreign Application Priority Data**

Sep. 30, 2010 (CA) 137374

(51) LOC (9) Cl. **08-05**

(52) U.S. Cl. **D8/90**

(58) **Field of Classification Search** D8/62, D8/90-94; D28/59; 132/76.4, 76.5; 451/28, 451/344, 354, 490, 492, 499, 512-513, 516, 451/523-524, 526; D32/40; D19/59; D21/505, D21/511
